UNITED STATES PATENT OFFICE.

JOSEPH KOENIG, OF MANITOWOC, WISCONSIN.

HOT-AIR ENGINE.

Application filed April 13, 1925. Serial No. 22,682.

This invention relates to hot air engines. Objects of this invention are to provide a hot air engine which has a minimum number of stuffing boxes or other similar parts likely to cause leaking or subject to wear, which is substantially enclosed as to the major portion of its structure, which may be readily placed under initial compression, which may be made in any desirable size, and which is substantially fool proof in operation.

Further objects are to provide a hot air engine in which a high degree of efficiency is attained, in which quick interchanges of heat are secured, and which is automatic in its operation, and may be controlled by a speed responsive governor, if desired, to insure a smooth and uniform action of the engine.

20 An embodiment of the invention is shown in the accompanying drawings, in which:—

Figure 1 is a plan view partly in section of the engine.

25 Figure 2 is a side elevation of the structure shown in Figure 1 with the air treating cylinders in vertical section.

Referring to the drawings, particularly Figure 1, it will be seen that the engine comprises a working cylinder 1 within which 30 is a piston 2 provided with a piston rod 3. This piston rod projects through a stuffing box 4 adapted to receive packing and also oil under pressure in accordance with the well known practice.

35 The outer end of the piston rod is secured to the cross head 5 which is connected by means of a pitman 6 with a crank pin 7 rigidly carried by the main shaft 8. A fly wheel 9 of any suitable weight is rigidly secured to the shaft and it is to be noted further from reference to Figure 1, that a 40 governor 10 is also carried directly by the shaft and oscillates a controlling rod 11 hereinafter described in greater detail.

45 From Figures 1 and 2, it will be noted that the working cylinder 1 is preferably mounted upwardly above the base 12 and approximately half way between the air treating cylinders indicated generally at A and B. These air treating cylinders are 50 identical in construction and are connected with opposite ends of the work cylinder 1 in a similar manner as will appear as the description proceeds, only one of the cylinders need, therefore, be described.

Referring to Figure 2, it will be seen that the cylinders are each provided with a main cylinder portion or shell 12 which is equipped with an outer head 13 and with an inner head 14. It is to be noted that the shell 12 extends to adjacent the rear of the device and is provided with an inturned or inwardly extending smaller shell 15 which extends to the inner cylinder head 14.

A stationary sleeve 16 is rigidly carried by the head 13 and slidably receives the elongated piston 17, such piston being rigidly attached to a piston rod 18 which in turn is guided through the plug 19. Preferably, the piston 17 is provided with a heat insulating lining 20, as indicated in Figure 2. The rear end of the piston rod 18 is provided with a relatively small piston 21 which slides within a small cylinder 22.

It is to be noted from Figure 2 that the cylinders 22 are connected by means of a pipe or conduit 23 and that these cylinders are preferably filled with a liquid such for instance as oil. The purpose of this construction is to insure simultaneous and reverse 70 operations of the pistons 17, as indicated in Figure 2, and it is obvious that the oil in the cylinders 22 will secure this reverse operation.

It is to be noted from Figures 1 and 2 85 that the working cylinder 1 has a relatively large pipe at each end, as indicated at 24, which extends to an annular chamber 25 surrounding the ends of each of the cylinders A and B. These annular chambers 90 communicate directly with the cylinders through the space between the stationary sleeve 16 and the outer shell 12.

A pair of smaller pipes 26 extend from opposite ends of the cylinder 1 to the forward ends of the small cylinders 22.

It is to be noted from reference to Figure 2 that the lower end of the cylinders A and B are provided with water jackets 27 so that such rear ends are chilled at all 100 times.

It is to be noted particularly from reference to Figure 2 that a plurality of heating pipes 28 extend from one portion of the annular channel or chamber 5 into the forward 105 end of the cylinder on a diametrically opposed side. These pipes are adapted to be heated in any suitable manner, and may, if desired, be enclosed by a casing 29 to house the heating flame of a burner 29' (see Fig. 110

ure 1) or similar member, the products of combustion passing out of the aperture 29" shown in Figure 2.

In operation, the system is preferably placed under compression by means of the valves 30, as shown in Figure 1, which are adapted to be connected to any suitable source of air pressure. In addition to this, it is preferable to supply a high pressure to one side of the piston 2 to turn the engine over when starting.

Consider for example, the condition when the piston 2 is approaching the rear end of its stroke, the air is discharged from the cylinder 1 into one of the cylinder A. This air passes into the annular chamber 25 and from thence rearwardly between the wall 12 and the stationary sleeve 16 and past the cool end of the cylinder where it is chilled and contracted. As the piston 2 more closely approaches the limit of its stroke, pressure builds up ahead of the piston 2 and is transmitted through the pipe 26 to the cylinder 22 associated with the cylinder A and thus causes the rearward travel of the piston 21 of such cylinder and the forward travel of the small piston in the other cylinder. This causes a similar motion of the piston 17. When the piston 17 of the cylinder A travels rearwardly it forces the air in a reverse direction between the shell 12 and the sleeve 16 and through the heated pipes 28, such air being discharged in a heated condition forwardly of the piston 17. This air is, therefore, quickly heated and expands and forces the piston 2 in a reverse direction. Obviously, as the piston 2 travels in a reverse direction the air is passed from the end of the cylinder which the piston is approaching, into the cylinder B, of the air treating portion of the apparatus, and is chilled, as previously described. However, as the end of the stroke is approached, the pistons 17 are moved in a reverse direction with consequent reverse operation of the piston 2, as previously described.

It is to be noted that when the piston 17 is in its outermost position adjacent the head 13 that has expelled the hot air through the tubes 28 into the cold end of the cylinder, through the passage between the casing 12 and the sleeve 16. However, when the piston 17 is in its rearmost position, as shown for the cylinder B, air has been forced in a reverse direction through the heated pipes, into the hot end of the cylinder B, through the same passages in a reverse direction from the cylinder A.

In order to provide for automatic control of the engine, the rocking shaft 11 from the governor 10 is provided with a valve 31 (see Figure 2) which controls communication between the annular chambers 25 of the cylinders A and B. Obviously, if the governor operates due to excessive speed, the

pressure in the two cylinders A and B is allowed to partly equalize, and consequently the effect of these cylinders is reduced temporarily and the speed of the engine decreased.

It will be seen that an extremely simple type of hot air engine has been provided which is efficient in operation, which is devoid of valves with the exception of the governor valve, and in which the working parts are enclosed with the single exception of the working piston rod 3 which extends through a packing gland. There is, therefore, a very small chance of leakage in this system and consequently an effective operation is maintained.

Although the invention has been described in considerable detail, it is to be understood that the invention may be variously embodied and is, therefore, to be limited only as claimed.

I claim:

1. A hot air engine comprising a working cylinder, a piston mounted therein, a pair of cylinders connected with opposite ends of said working cylinder, each of said pair of cylinders having air circulating pistons therein provided with piston rods, and having heating and cooling means, a pair of auxiliary cylinders into which said piston rods project, pistons fitting said auxiliary cylinders and carried by said piston rods, said auxiliary cylinders containing a liquid and having their outer ends connected, and means whereby the system may be placed under initial compression.

2. A hot air engine comprising a working cylinder, a piston mounted therein, a pair of cylinders connected with opposite ends of said working cylinder, each of said pair of cylinders having air circulating pistons therein provided with piston rods and having heating and cooling means, a pair of auxiliary cylinders into which said piston rods project, pistons fitting said auxiliary cylinders and carried by said piston rods, said auxiliary cylinders containing a liquid and having their outer ends connected, and pipes connecting said auxiliary cylinders with opposite ends of said working cylinder.

3. A hot air engine comprising a working cylinder, a pair of air conditioning cylinders having at one end external heated means through which the air is adapted to pass, said pair of cylinders having the other ends cooled, pistons within said pair of cylinders and controlling the flow of air through said heating means, means connecting opposite ends of said working cylinder with said pair of cylinders, and means controlled by the working piston for operating the pistons in the air conditioning cylinders.

4. A hot air engine comprising a working cylinder, a pair of air conditioning cylinders having at one end external heated means

- through which the air is adapted to pass, said pair of cylinders having the other ends cooled, pistons within said pair of cylinders and controlling the flow of air through said 5 heating means, means connecting opposite ends of said working cylinder with said pair of cylinders, means controlled by the working piston for operating the pistons in the air conditioning cylinders, rotary means 10 driven from the working piston, a governor operated by said rotary means, and a valve operated by said governor and controlling intercommunication of said pair of cylinders.
- 15 5. A hot air engine comprising a pair of air cylinders each having closed ends, a sleeve carried by one end and projecting into the cylinder and spaced from the walls thereof, an annular chamber surrounding such end of the cylinder and communicating 20 with the space between said sleeve and the cylinder walls, a plurality of heated pipes extending from the annular chamber and opening through the head of the cylinder, a piston mounted within each cylinder and fitting within said sleeve, cooling means for each cylinder remote from the heating pipes, a working cylinder having opposite ends connected with the annular chambers of said 25 pair of cylinders, a working piston within said working cylinder, and means controlled by said working piston for controlling the position of the first mentioned pistons.
- In testimony that I claim the foregoing I have hereunto set my hand at Manitowoc, 30 in the county of Manitowoc and State of Wisconsin.

JOSEPH KOENIG.
